DESIGN FOR AN ELECTRIC OZONIZER

William A. Pardey, Portland, and Livy Stipp,
Oregon City, Oreg.

Application February 27, 1939, Serial No. 83,228

Term of patent 14 years

To all whom it may concern:

Be it known that we, William A. Pardey and Livy Stipp, citizens of the United States, residing at Portland, in the county of Multnomah and State of Oregon, and Oregon City, county of Clackamas, and State of Oregon, respectively have invented a new, original, and ornamental Design for an Electric Ozonizer, of which the following is a specification, reference being had to the accompanying drawings, forming part thereof.

Fig. I is a front elevational view of an electric ozonizer embodying our new design.

Fig. II is an end elevational view.

Fig. III is a rear elevational; and

Fig. IV is a top plan view thereof.

We claim:

The ornamental design for an electric ozonizer, as shown.

WILLIAM A. PARDEY.
LIVY STIPP.
